US00D872753S

(12) **United States Design Patent** (10) Patent No.: **US D872,753 S**
(45) Date of Patent: **** Jan. 14, 2020**

(54) **DISPLAY SCREEN OR PORTION THEREOF WITH GRAPHICAL USER INTERFACE FOR A MEDICAL DEVICE**

D574,010 S 7/2008 Borovsky D14/487
D575,792 S 8/2008 Benson
D593,117 S 5/2009 Lettau D14/488
D594,018 S 6/2009 Ball et al.
D611,055 S * 3/2010 Jonasson D14/486

(71) Applicant: **Maquet Cardiopulmonary GmbH**, Rastatt (DE)

(Continued)

(72) Inventors: **Ralph J. Ebler**, Warwick, NY (US); **Daniel Medart**, Stahnsdorf (DE)

JP 1294399 1/2007
JP 1437253 3/2012

(73) Assignee: **MAQUET CARDIOPULMONARY GmbH**, Rastatt (DE)

(Continued)

(**) Term: **15 Years**

(21) Appl. No.: **29/646,368**

(22) Filed: **May 3, 2018**

CLAIM

The ornamental design for a display screen or portion thereof with graphical user interface for a medical device, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface for a medical device. The broken lines showing the display screen or portion thereof form no part of the claimed design.
